FIG. 1.

FIG. 2.

FIG. 3.

FIGURE 1 is a perspective view of a floor treating machine showing our new design, the view being taken from the front and one side of the machine;

FIGURE 2 is a side elevation of said one side of said machine; and

The side not shown has substantially the same appearance as the side shown.

The dominant features of our design reside in the portions shown in full lines.

We claim:

The ornamental design for a floor treating machine or similar article, substantially as shown and described.
